US0D1107538S

(12) **United States Design Patent** (10) **Patent No.:** **US D1,107,538 S**
(45) **Date of Patent:** **** Dec. 30, 2025**

(54) **MULTIPLE MAGNET POST MOUNT**

(71) Applicant: **Gary Truesdale**, El Segundo, CA (US)

(72) Inventor: **Gary Truesdale**, El Segundo, CA (US)

(**) Term: **15 Years**

(21) Appl. No.: **29/881,813**

(22) Filed: **Jan. 6, 2023**

(51) **LOC (15) Cl.** **13-99**

(52) **U.S. Cl.**

USPC **D13/183**; D8/349

(58) **Field of Classification Search**

USPC D8/14, 37, 349, 354, 355, 363, 373, 380,
D8/384, 394, 396, 499; D13/183

CPC B60B 17/00; B60B 15/00; B60B 13/04;

Primary Examiner — Erich G Herbermann

Assistant Examiner — Rene H. Kadoo

(57) **CLAIM**

The ornamental design for a multiple magnet post mount as shown and described.

DESCRIPTION

FIG. 1 is a front view of the multiple magnet post mount showing my new design;
FIG. 2 is a right view thereof;
FIG. 3 is a left view thereof;
FIG. 4 is a top view thereof;
FIG. 5 is a bottom view thereof;
FIG. 6 is a back view thereof;
FIG. 7 is a top, front, and left isometric view thereof;
FIG. 8 is a bottom, back, and right isometric view thereof;
and,
FIG. 9 is a top, front, and left isometric view showing the multiple magnet post mount in use on a post.
The broken lines are directed to environment and form no part of the claimed design.

1 Claim, 7 Drawing Sheets
